Primary Examiner—Alan P. Douglas*Assistant Examiner*—M. N. Pandozzi*Attorney, Agent, or Firm*—Mueller and Smith[57] **CLAIM**

The ornamental design for spherical beverage container with handle, as shown and described.

DESCRIPTION

FIG. 1 is a right side view of a first embodiment of the spherical beverage container with handle showing my new design;

FIG. 2 is a rear view thereof;

FIG. 3 is a front view thereof;

FIG. 4 is a top view thereof;

FIG. 5 is a bottom view thereof;

FIG. 6 is a right side perspective view of a second embodiment of the spherical beverage container with handle showing my new design, the left side being a mirror image;

FIG. 7 is a rear view thereof;

FIG. 8 is a front view thereof;

FIG. 9 is a top view thereof;

FIG. 10 is a bottom view thereof;

FIG. 11 is a right side perspective view of a third embodiment of the spherical beverage container with handle showing my new design, the left side being a mirror image;

FIG. 12 is a rear view thereof;

FIG. 13 is a front view thereof;

FIG. 14 is a top view thereof; and,

FIG. 15 is a bottom view thereof.
